(57) **CLAIM**

The ornamental design for a trocar, as shown and described.

DESCRIPTION

FIG. 1 is a perspective view of a trocar showing our new design.

FIG. 2 is an exploded perspective view thereof.

FIG. 3 is a front view thereof.

FIG. 4 is a side view thereof.

FIG. 5 is a side view thereof opposite to that shown in FIG. 4.

FIG. 6 is a back view thereof.

FIG. 7 is a top view thereof; and,

FIG. 8 is a bottom view thereof.

The broken line showing is for illustrative purposes only and forms no part of the claimed design.
